UNITED STATES PATENT OFFICE.

FRANK RHIND, SAMUEL G. STODDARD, AND GEORGE W. BALDWIN, OF BRIDGEPORT, CONNECTICUT, ASSIGNEES TO THE BRIDGEPORT BRASS COMPANY, OF SAME PLACE.

DESIGN FOR A LAMP-HOLDER.

SPECIFICATION forming part of Design No. 25,353, dated April 7, 1896.

Application filed February 4, 1896. Serial No. 578,060. Term of patent 14 years.

To all whom it may concern:

Be it known that we, FRANK RHIND, SAMUEL G. STODDARD, and GEORGE W. BALDWIN, citizens of the United States, residing 5 at Bridgeport, in the county of Fairfield and State of Connecticut, have invented and produced a new and original Design for Holders for Bicycle-Lamps; and we do declare the following to be a full, clear, and exact description of the same, reference being had to the accompanying drawing, forming a part thereof.

The figure is a perspective of a lamp-holder embodying our novel design. 15 The leading feature of our design consists in a clamp having two arms, each of which has a depressed portion, then a substantially straight portion, and then another depressed portion at its ends.

B is a clamp consisting of two arms, each 20 of which is depressed at 3 and having a substantially straight portion 2 and bent outwardly and inwardly at its end to form another depressed portion 4. The two arms join each other at 5 and the depressions of 25 the two arms are opposite and face each other.

What we claim is—

The design for a bicycle-lamp holder substantially as shown and described.

In testimony whereof we affix our signatures in presence of two witnesses.

FRANK RHIND.
SAMUEL G. STODDARD.
GEORGE W. BALDWIN.

Witnesses:

E. W. FAIRCHILD,
NETTIE S. WELLS.
